UNITED STATES PATENT OFFICE.

JOHN SPRANGERS, OF KAUKAUNA, WISCONSIN.

MUSICAL CLOCK.

SPECIFICATION forming part of Letters Patent No. 408,903, dated August 13, 1889.

Application filed February 19, 1889. Serial No. 300,434. (No model.)

To all whom it may concern:

Be it known that I, JOHN SPRANGERS, of Kaukauna, in the county of Outagamie, and in the State of Wisconsin, have invented certain new and useful Improvements in Musical Clocks; and I do hereby declare that the following is a full, clear, and exact description thereof.

My invention relates to musical clocks; and it consists in certain peculiarities of construction and combination of parts, to be herein-after described with reference to the accompanying drawings and subsequently claimed.

In the drawings, Figure 1 represents a portion of the frame for a clock-train, a minute-post provided with a cam that forms part of my invention, a bell-crank lever in position to be actuated by the cam, and a sectional view of a portion of a music-box attached to a clock-case and arranged with relation to the bell-crank lever, the section being taken on line 1 1 of Fig. 2; Fig. 2, a plan view of a portion of the music-box arranged with relation to the bell-crank lever and illustrating certain attachments constituting parts of my invention; Fig. 3, a section on line 3 3 of Fig. 2; Fig. 4, a detail view illustrating the gear-wheel that is attached to the music-box cylinder, the stop-lever that engages said gear-wheel, and a spring cut-off for said stop-lever; and Fig. 5 is a detail elevation of the parts shown in the preceding figure, certain of these parts being shown in section.

Referring by letter to the drawings, A represents one side of the frame for an ordinary clock-train, B a supplemental cross-brace attached to the standards of said side of the frame, and C a disk pivoted to the cross-brace and provided with arms D D', arranged at right angles to each other to form a bell-crank, these arms being screw-threaded to said disk to permit of longitudinal adjustment to regulate the leverage.

Fast on the minute-post E of the clock-train is a cam F, arranged to impinge against the bent free end b of the arm D of the bell-crank lever, and the other arm D' of said bell-crank is arranged to lie just above the spring-controlled stop-lever G of a music-box of ordinary construction, attached by any suitable means to the casing H of the clock to which my invention may be applied.

The lever-arm D' is controlled by a spiral spring c, that connects it with the train-frame of said clock, and said lever-arm is provided with an angular finger d, designed to come in the path of the music-box fan I at the instant the stop-lever G is actuated to bring its angular point e out of engagement with the gear-wheel J, that has a clutch-pin connection f with the music-box cylinder K.

Attached to the frame of the music-box is a strip L, of spring metal, having the free end g thereof bent to lie adjacent to the gear-wheel J and normally rest upon the angular point e of the stop-lever G. Secured to the bent end of the spring-metal strip is a finger h, that straddles the gear-wheel J and comes in the path of the clutch-pin f, connecting this gear-wheel and the cylinder K. The bent strip L forms a spring cut-off designed to close the opening in the gear-wheel J, with which the stop-lever G engages at the instant the angular point e of said lever is withdrawn, said strip remaining in position to accomplish this result long enough to permit said opening to pass the lever-point.

While the above-described construction of the spring cut-off is the one preferred, it is obvious that the strip L may be of material other than spring metal controlled by a spring of spiral or other form.

Supposing the spring cut-off to be in position between the point e of the stop-lever G and the adjacent side of the gear-wheel J, the latter and the cylinder K will be in the act of rotation, and at a certain time during this rotation the clutch-pin f will come against the finger g on said cut-off, and thereby cause the latter to rise up and permit said point of the stop-lever to assume position ready to engage the opening in said gear-wheel when the latter has completed a revolution. The spring cut-off will now rest upon the point e of the stop-lever G ready to drop between it and the gear-wheel the instant the latter and said lever-point are again disengaged. The cam F on the minute-post E of the clock-train is so timed that at a certain fraction of an hour it will tilt the bell-crank lever against the resistance of the spring c to cause the arm D' thereof to press upon the stop-lever G of the music-box, and thereby disengage this latter lever and the gear-wheel J, thus permitting

the spring cut-off L to interpose itself between the point e of said stop-lever and said gear-wheel, while at the same time the angular finger d on said arm of the bell-crank lever 5 comes in the path of the music-box fan I to prevent rotation of the cylinder K, this operation being instantaneous, and taking place when the point marked i on said cam has reached the bent end b of the arm D of said 10 bell-crank.

Should my invention be applied to a striking-clock, the parts would be so arranged that at the time the point marked j on the cam F reached the bent end b of the bell-crank- 15 lever arm D the striking mechanism would operate, and when the point marked k on said cam passed said bent end of the lever-arm the contraction of the spring c would cause a tilt of the bell-crank lever reverse to that al- 20 ready described to bring the angular finger d on its arm D' out of the path of the fan I of the music-box, thereby allowing the latter to play until the stop-lever G and gear-wheel J again engage.

25 As shown, the cam F is a double one and so timed that the music-box will play every half hour; but it is obvious that said cam may be of such contour that the interval between airs from said music-box may be lengthened 30 or shortened, this being a mere matter of preference.

By having the arms D D' of the bell-crank lever longitudinally adjustable the leverage can be accurately determined and the device 35 readily applied to clocks of varying dimensions without the necessity of making a separate size of bell-crank for each size of clock.

Having thus fully described my invention, what I claim as new, and desire to secure by 40 Letters Patent, is—

1. In a clock, the combination of the minute-post provided with a cam, a bell-crank lever arranged to have one arm thereof in contact with the cam, a music-box arranged to 45 have its stop-lever in the path of the other arm of the bell-crank lever, and a spring cut-off secured to the music-box to be automatically interposed between the stop-lever and adjacent gear-wheel at a predetermined instant for a 50 certain interval of time, substantially as set forth.

2. In a clock, the combination of the minute-post provided with a cam, another arm of the bell-crank lever arranged to have one arm thereof in contact with the cam, a music-box 55 arranged to have its stop-lever in the path of the bell-crank lever, a spring cut-off secured to the music-box to be automatically interposed between the stop-lever and adjacent gear-wheel at a predetermined time, and a fin- 60 ger secured to the cut-off to come in the path of the clutch-pin uniting said gear-wheel and music-box cylinder, substantially as set forth.

3. In a clock, the combination of the minute-post provided with a cam, a bell-crank lever 65 having longitudinally-adjustable arms and arranged to be actuated by the cam, and a music-box arranged to be set in motion by the joint action of said cam and bell-crank lever at predetermined intervals, substan- 70 tially as set forth.

4. In a clock, the combination of the minute-post provided with a cam, a bell-crank lever actuated by the cam and having one of its arms arranged to actuate the stop-lever of a suitably-positioned music-box, and a finger 75 secured to said arm of the bell-crank lever to come in the path of the music-box fan for a predetermined interval of time, substantially as set forth.

5. In a clock, the combination of the minute-post provided with a cam, a bell-crank lever fulcrumed to a bearing on the train-frame and arranged to be actuated by the cam, a music-box positioned to have its stop-lever 85 actuated by the bell-crank lever, a finger on said lever arranged to come in the path of the music-box fan when the stop-lever is actuated, and a spring cut-off arranged on said music-box to interpose itself between said 90 stop-lever and the adjacent gear-wheel at the same instant that said finger comes into position with relation to said fan, substantially as set forth.

In testimony that I claim the foregoing I 95 have hereunto set my hand, at Kaukauna, in the county of Outagamie and State of Wisconsin, in the presence of two witnesses.

JOHN SPRANGERS.
